CLAIM

The ornamental design for mobile phone, as shown and described.

DESCRIPTION

2. Mobile phone

FIG. 2.1 is a front view of a first embodiment of a mobile phone, showing my new design;

FIG. 2.2 is a back view thereof;

FIG. 2.3 is a left side view thereof;

FIG. 2.4 is a right side view thereof;

FIG. 2.5 it a top plan view thereof;

FIG. 2.6 is a bottom plan view thereof;

FIG. 2.7 is a front perspective view thereof; and

FIG. 2.8 is a back perspective view thereof.

The broken lines show portions of mobile phone that form no part of the claimed design.
